J. D. Marshbank, of Lancaster, Pa.

assor. to

Himself and W. McConkey, of same place.

Letters Patent, No. 1341, Dated Nov. 13th 1860.

The schedule referred to in these Letters Patent and making part of the same.

Des. 1341

To all whom it may concern:

Be it known, that J. J. D. Marshbank, of Lancaster City, County of Lancaster and State of Pennsylvania have invented a new ornament for Stove Doors of Cook Stoves, and I do hereby declare that the following is a full, and exact description thereof, reference being had to the accompanying drawings, and to the letters of reference marked thereon, making a part of this Specification.

The nature of my invention consists in the raised ornament on the side doors.

A. represents the door.

B. the ornament raised upon it.

What I claim as my invention and desire to secure by Letters Patent, is: the arrangement of ornamental figure and form represented in the accompanying drawings, forming the ornamental Design for the doors of a Cook Stove.
